UNITED STATES PATENT OFFICE.

HARRY C. HUBBELL, OF WEST SPRINGFIELD, MASSACHUSETTS, ASSIGNOR TO WICO ELECTRIC COMPANY, OF WEST SPRINGFIELD, MASSACHUSETTS, A CORPORATION OF MASSACHUSETTS.

IGNITION SYSTEM FOR BURNERS.

Application filed April 2, 1925. Serial No. 20,249.

This invention relates to improved means for controlling the ignition means of a burner and, while the invention is capable of other and general applications, it has been 5 developed and is particularly suitable for use in connection with oil burners.

The invention will be disclosed in a form developed for use in connection with electrical or spark ignition means and as adapted 10 to cut in and cut out such an ignition means whenever necessary. In certain respects, as will be evident from the description to follow, the invention is not restricted to the use of spark ignition means and might, for example, be made to alternately reduce and enlarge the flame of a gas pilot at proper times, according to the necessity therefor as manifested by the presence or lack of a flame from the burner. The reference hereinafter 15 to spark ignition is, therefore, not necessarily intended to exclude all other forms of ignition means although the spark ignition means is preferred.

The problem of this invention may be very 25 simply stated. It is to cut out the ignition means as soon as the burner has been ignited and to render the ignition means again available for the igniting function as soon as the burner stops. The solution of the problem 30 is not so easy as will be evident from a study of the prior art, which shows that the problem has been attacked from many widely differing angles. Among the more common 35 forms of control, found in the prior art is that which functions according to time. That is the ignition is cut in on starting the flow of fuel to the burner and remains in for a definite time interval. This is not as 40 satisfactory as it should be because it is entirely possible for the time interval to elapse without ignition actually occurring. The ignition should be stopped only after its work has actually been accomplished, as 45 manifested by a flame issuing from the burner, which seems to require a control responsive to burner heat. A representative type of such heat control is the flame type thermostat found in the prior art as operating a switch or valve. Such a thermostat, 50 while apparently suitable from theoretical considerations, does not prove satisfactory in practice because it is not sufficiently quick acting for the purpose. The difficulty arises because the thermostat is subjected to very

wide temperature ranges and thus to relatively large degrees of expansion and contraction. There is bound to be, under any conditions, an appreciable time interval to cause the thermostat to close the switch or valve and under some conditions, which are 55 not necessarily infrequent, there may be long delays. For example, if the thermostat cuts out a switch in the ignition circuit after the burner has been ignited and the burner is later stopped and then again started before 60 the fire box has cooled materially, the thermostat will not immediately close the switch because it has not cooled sufficiently and oil will be thrown into the fire box to be later 65 ignited with possible disastrous results. 70 While all sorts of precautions have been taken to cope with such emergencies, instances of explosions directly traceable to slow action of an ignition controlling thermostat have occurred. The thermostat is 75 therefore not wholly reliable and does not adequately meet all the conditions which must be met in practice to insure safe and reliable automatic operation of an oil 80 burner.

The object of this invention is to provide a controlling device which is responsive to heat, as is the thermostat, but which will function to quickly cut out the ignition means once its work has been accomplished, 85 as manifested by the presence of flame at the burner, and which after the burner has stopped will again cut in the ignition simultaneously with the starting of the burner and without any delay.

In attaining this object, a novel form of control device is arranged in an electrical circuit which also includes an electrically operated device for cutting in and out the ignition means. The control device includes 90 an air gap and through which no current flows when the burner is not ignited. The invention depends, it is thought, on the ionization of the air between the electrodes of the control device caused by the heat from the flame of the ignited oil burner and the practical result is that, on such a condition, current sufficient to operate said device flows 100 through the circuit. In its simplest form the control device consists of two spaced electrodes with an air gap therebetween and it 105 may be an ordinary spark plug.

In addition to the control device, which

functions to open a switch in the ignition circuit, means are provided to hold the switch open and such means are arranged to be automatically released when the burner stops, whereby the switch is automatically reset ready for subsequent operation. The ignition means does not then function, however, but its starting is deferred until, and made dependent on, the starting of the burner. For example, the room thermostat, which controls the starting of the burner, is made to also control the starting of the ignition means.

Other features and advantages will appear from the following description and in the illustrative embodiment of the invention in the accompanying drawings, in which:

Fig. 1 is a fragmentary sectional elevational view of an automatically controlled oil burning furnace showing the disposition of the control device and ignition means therein; and

Fig. 2 is a diagrammatical view showing the electrical connections for controlling the burner, an electrical ignition system and a control therefor.

Referring to these drawings: the automatic oil burner may obviously be of any suitable type and that shown herein is given solely by way of illustrative example. There are many other types which would be equally suitable and with which my invention could as readily be used. As shown, the oil burner is of the centrifugal type and involves a cup atomizer 5 carried on the upper end of a hollow vertical shaft 6 through which oil is drawn up to the atomizer from a reservoir 7 by the action of centrifugal force. Shaft 6 is driven, as by spiral gears 8, from a horizontal shaft 9 connected to the armature of an electric motor 10. The latter, the reservoir and the supporting casing for shaft 6 are shown as mounted on a common bed plate 11, one end of which extends into the ash pit 12 of furnace F. The fire box 13 has a central opening 14 in its bed 15 through which shaft 6 extends and through which combustion supporting air enters. The oil, in the form of a fine mist or spray, is thrown out horizontally from cup 5 and is adapted to be ignited from a spark plug 16, suitably supported as shown.

The control device, which as stated may be a spark plug, is shown in that form at 17 and includes an air gap 18 between two electrodes 19 and 20. The control device may be supported like the spark plug and I prefer to arrange it as shown at a distance therefrom.

The oil burner motor 10 is arranged to be started and stopped under thermostatic control, desirably from a room thermostat acting in any suitable manner to operate a switch in the motor circuit. For convenience, the room thermostat and switch have

been shown in conventional form at 21 and 22, respectively, in Fig. 2 and the switch is interposed in one of the supply wires 23 and 24 leading from a suitable source of alternating current to the motor 10. Other usual safety devices, in common use with oil burners, may be interposed in the circuit to motor 10 and I have not attempted to illustrate more than the fundamental parts necessary to a proper understanding of this invention.

The ignition system comprises, in addition to spark plug 16, a transformer T, of which 25 represents the core, 26 the primary, 27 the secondary and 28 an auxiliary secondary for use in connection with the control device 17. The primary winding 26 is connected in circuit with the supply wires 23 and 24 but beyond the motor 10 and includes a switch, comprising the contacts 29 and 30 by means of which the primary winding may be cut out of circuit without stopping motor 10. One terminal of the primary is connected directly to wire 23 and the other terminal is connected by a wire 31 to contact 30 which is stationarily supported, as from an insulating standard 32 from a bed plate 33. Contact 29 is mounted on a metallic lever 34, which is connected to wire 24 and is pivotally supported at one end, as from an insulating standard 35, also mounted on bed 33. A spring 36 urges lever 34 upwardly and tends to hold contacts 29 and 30 engaged. The secondary 27 is connected by wires 37 and 38 to the electrodes of spark plug 16. It will be seen that there are two switches controlling the primary winding of the transformer T and thus the high tension current to spark plug 16. When switch 22 opens the other switch closes, as will appear, so that when the thermostat 21 causes switch 22 to close and start the oil burner motor 10 it also causes the energization of the transformer and sparks are produced across the electrodes of plug 16 to ignite the oil. In the event of ignition, the contacts 29 and 30 are caused to separate, as will appear, and cut out the primary of the transformer, thereby stopping the ignition means.

The separation of contacts 29 and 30 is effected by electrical means adapted to be energized by current from the auxiliary secondary 28, which current is permitted to flow, at least to an extent sufficient to perform the function, only when a degree of heat, such as that due to the flame from the oil burner, exists in the fire box. The lever 34 has attached thereto an armature 39 which is adapted to be attracted by a solenoid 40, mounted on base 33. One terminal of solenoid 40 is connected by a wire 41 to electrode 20 of the control plug 17 and the other terminal is connected by a wire 42 to one terminal of the auxiliary secondary 28. The other terminal of the latter is con-

nected to the wire 37, to which the electrode 19 of the control plug is also connected. This wire 37 may be grounded, as indicated.

On energization of solenoid 40 a quick, strong downward pull is imparted to lever 34 and thereby the contacts 29 and 30 are separated, which cuts out the primary of the transformer and thus cuts off the current flowing to solenoid 40. To hold the switch lever 34 in its lower position, a second solenoid 43 is provided which similarly acts on a second plunger 44 connected to lever 34. This solenoid is bridged across the supply wires 23 and 24 and controlled by a switch comprising two contacts 45 and 46, which are normally open but are adapted to be engaged by the first downward movement of lever 34. The contact 45 is fixed to lever 34 and thus connected to wire 24. Wire 23 is connected by a wire 47 to one terminal of solenoid 43 and the other terminal of the latter is connected by a wire 48 to contact 46. The latter is slidably mounted in a standard 49, insulated from bed 33, and is urged upwardly by a spring 50 to the limit permitted by a stop 51. The contacts 45 and 46 do not quite touch so that the circuit to solenoid 43 is normally open but can be closed quickly, on the first downward movement of lever 34. The solenoid 40 gives the quick, strong pull necessary to cause a quick and sharp separation of contacts 29 and 30. The solenoid 43 then comes into play to hold the contacts separated, even after current ceases to flow in solenoid 40, and solenoid 43 is so designed as to consume a very small amount of power, say five watts or thereabouts. It can, therefore, be left in circuit for long intervals with an exceedingly small expense for power. The solenoid 40, being used only intermittently and for intervals of short duration, can be wound to give the desired results and it matters little if more power is consumed. The solenoid 43 remains energized as long as the motor 10 continues to operate but as soon as the thermostat 21 opens switch 22 to stop the motor it also opens the circuit to solenoid 43. The spring 36 then restores the lever 34 and engages contacts 29 and 30. This action ensues immediately after the current is cut off from motor 10 by the opening of switch 22 and on again closing the latter the primary of transformer T is supplied with current as quickly as is motor 10. Consequently, the motor and ignition means start simultaneously and there can be no delay between the operation of these two elements. At the same time the control device causes the ignition means to be cut out immediately after the burner is ignited.

The operation may be summarized as follows:—When the oil burner is not working the parts are in the relative positions illustrated in Fig. 2. The ignition means is like-

wise idle and no current is being consumed thereby or by the switch holding solenoid 43. As soon as operation of the oil burner is required, as manifested by thermostat 21, switch 22 is closed by the latter. The motor 10 is thus started and oil is discharged into the fire box by the atomizer. At the same time, the transformer is supplied with current and ignition sparks are produced at the spark plug 16. The spray of oil from the atomizer follows the starting of the motor and is at least slightly deferred while the sparks are produced at the plug simultaneously with the starting of the motor. Consequently, the ignition means is available an instant before it is needed.

By preference, the secondary 27 is designed to give a high voltage before the spark starts so as to insure its starting and, after the spark is jumping at the plug, the current is such that the ends of the electrodes are brought to a glowing temperature. The result is virtually an arc, as distinguished from the ordinary jump spark, and the practical result is an intense heat which is sufficient to gasify fuel oils of low volatility, whereby ignition of fuels, difficult to ignite by a simple high tension spark, is insured. The use of such an electrical ignition means, demands that the same be cut out immediately that it is no longer needed to minimize destructive effects on the electrodes of the plug. There is thus an additional reason, over the ordinary reason of needless waste of energy, for cutting out the ignition means promptly.

This result is insured by the special control device which is arranged to respond only to the high temperature due to the oil burner flame. This device accomplishes its work instantaneously, or at least apparently so, and with precision and certainty. The heat from the oil burner flame increases the conductivity of the air gap between the terminals of the control plug and current flows to the solenoid to a degree sufficient to impart a quick strong pull to armature 39. The contacts 29 and 30 are immediately separated, thereby opening the primary circuit of the transformer and cutting out of action both the ignition secondary and the secondary used to supply the control plug. At the same time contacts 45 and 46 are engaged to energize the solenoid 43 which holds the contacts 29 and 30 separated until the oil burner motor stops. At that time switch 22 opens and contacts 29 and 30 immediately engage again, thus throwing the control of the ignition means back on the thermostat switch so that it will be instantly available when motor 10 is again started.

By analogy it will be readily apparent to those skilled in the art that the ignition controlling means may readily be adapted to operate a valve as well as the switch dis-

closed, whereby the control may have a field of service in connection with ignition means other than of an electrical character.

While in the preceding description the control device is described as an air gap, it is recognized that the preferred form of the invention may be varied in numerous ways and still operate in essentially the same broad manner and upon the same broad principle. The air gap is the best example of a control device which when subjected to heat will function in the manner above set forth but it is recognized that other control devices may be used in the same general manner, wherefore this invention is not to be restricted to the particular form herein specifically set forth.

The invention turns largely on the particular control device as combined with other elements to effect the results disclosed. This device is the key to the successful solution of the ignition control problem because it can be made as sensitive as need be and instantly responsive to the oil burner flame. It has been demonstrated that the heat from a lighted match held in proximity to the gap of the control plug will cause an immediate opening of a switch by electrical means. The control device is thus the governing element in a broad combination with other elements of an ignition system. It follows that the details of such system and the particular types of the broad elements of the combination may be varied as desired and that the details disclosed are exemplary in character. It is the intention to claim the invention in the broadest possible legal manner.

What I claim is:

1. In combination, a burner, an ignition device therefor having an active condition for ignition of fuel from the burner and an inactive condition, means to automatically start and stop the burner and to render the ignition device active simultaneously with the starting of the burner, means to render the ignition device inactive independently of the first named means, electrical means to operate the last named means, a source of electrical energy for said electrical means, a control device associated with the burner and including two terminals with an air gap therebetween, and a series circuit including said source, electrical means and terminals, said gap adapted to be heated by the burner flame and when so heated to permit sufficient current to flow in said circuit to operate said electrical means.

2. In combination, a burner, an ignition device therefor having an active condition for ignition of fuel from the burner and an inactive condition, means to automatically start and stop the burner and to render the ignition device active simultaneously with the starting of the burner, means to render

the ignition device inactive independently of the first named means, electrical means to operate the last named means, a source of electrical energy for said electrical means, a control device associated with the burner and including two terminals with an air gap therebetween, and a circuit including said source, electrical means and terminals, said air gap adapted to be heated by the burner flame and when so heated to permit sufficient current to flow in said circuit to operate said electrical means, and means operable by the first named means when it stops the burner to reset the means whereby the ignition device was rendered inactive.

3. In combination, a burner, automatic means to start and stop the same, electrical ignition means therefor including an electrical circuit arranged to be closed and opened by the starting and stopping, respectively, of the burner under the control of said automatic means, said circuit also including a normally closed switch, electrically operated means adapted when energized to open said switch, and a control device arranged in circuit with said electrically operated means and a suitable source of electricity, said device including two spaced terminals with an air gap therebetween and so located that said medium is heated by flame from the burner, said medium when so heated becoming conductive and permitting flow of current across said terminals to energize said electrically operated means and open said switch to cut out said ignition means.

4. In combination, a burner, automatic means to start and stop the same, electrical ignition means therefor including an electrical circuit arranged to be closed and opened by the starting and stopping, respectively, of the burner under the control of said automatic means, said circuit also including a normally closed switch, electrically operated means adapted when energized to open said switch, a control device arranged in circuit with said electrically operated means and a suitable source of electricity, said device including two spaced terminals with an air gap therebetween and so located that said medium is heated by flame from the burner, said medium when so heated becoming conductive and permitting flow of current across said terminals to energize said electrically operated means and open said switch to cut out said ignition means, and means to hold said switch open until the burner is stopped by said automatic means and to then permit said switch to be closed.

5. In combination, a burner, spark electrodes positioned to ignite the fuel from the burner, a transformer, a secondary circuit from the transformer including said electrodes, a primary circuit from the trans-

- former including a self closing and normally closed switch therein, automatic means for starting and stopping the burner and for closing and opening said primary circuit, electrical means adapted when energized to open said switch, a second set of spaced electrodes adjacent said burner, and a secondary circuit from said transformer including said electrical means and said second set of electrodes.
6. In combination, a burner, spark electrodes positioned to ignite the fuel from the burner, a transformer, a secondary circuit from the transformer including said electrodes, a primary circuit from the transformer including a self closing and normally closed switch therein, automatic means for starting and stopping the burner and for closing and opening said primary circuit, electrical means adapted when energized to open said switch, a second set of spaced electrodes adjacent said burner, a secondary circuit from said transformer including said electrical means and said second set of electrodes, a second electrical means adapted when energized to hold said switch open, a supply circuit therefor controlled by said automatic means, and a switch in the last named circuit adapted to be closed by the opening of the first switch and opened by the closing of the latter.
7. The combination with an oil burner, an electric motor to drive the same and a thermostat operated switch to start and stop the motor, of spark electrodes for igniting the oil from the burner, a transformer to produce sparks across the electrodes and connected in circuit with said motor so as to be subject to control by said switch, a self closing switch also in circuit with the transformer and adapted when opened to cut out the transformer without stopping the motor, a second pair of spaced electrodes arranged adjacent the burner, electrical means adapted when energized to open the self closing switch, and a circuit from the transformer including said electrical means and said second pair of electrodes, a second electrical means adapted when energized to hold the self closing switch open, a circuit from the motor circuit connected in shunt therewith and adapted to supply said second electrical means, and a switch in said shunt supply circuit adapted to be closed by the opening of the self closing switch.
8. The combination with an oil burner, an electric motor to drive the same and a thermostat operated switch to start and stop the motor, of spark electrodes for igniting the oil from the burner, a transformer to produce sparks across the electrodes and connected in circuit with said motor so as to be subject to control by said switch, a self closing switch also in circuit with the transformer and adapted when opened to cut out the transformer without stopping the motor, a second pair of spaced electrodes arranged adjacent the burner, electrical means adapted when energized to open the self closing switch, and a circuit from the transformer including said electrical means and said second pair of electrodes.
9. In combination, a burner, means for starting and stopping the same, an ignition device having an active condition for ignition of the fuel from the burner and an inactive condition, means for rendering said device active simultaneously with the starting of the burner, electrical means effective when energized to render said device inactive and a series electrical circuit including said electrical means with an air gap and a source of high potential, whereby the air gap forms a break in said circuit, said air gap being subjected to the heat from the burner and when heated thereby permitting a flow of current across said gap to said electrical means.
- In testimony whereof I have affixed my signature.

- former including a self closing and normally closed switch therein, automatic means for starting and stopping the burner and for closing and opening said primary circuit, electrical means adapted when energized to open said switch, a second set of spaced electrodes adjacent said burner, and a secondary circuit from said transformer including said electrical means and said second set of electrodes.
6. In combination, a burner, spark electrodes positioned to ignite the fuel from the burner, a transformer, a secondary circuit from the transformer including said electrodes, a primary circuit from the transformer including a self closing and normally closed switch therein, automatic means for starting and stopping the burner and for closing and opening said primary circuit, electrical means adapted when energized to open said switch, a second set of spaced electrodes adjacent said burner, a secondary circuit from said transformer including said electrical means and said second set of electrodes, a second electrical means adapted when energized to hold said switch open, a supply circuit therefor controlled by said automatic means, and a switch in the last named circuit adapted to be closed by the opening of the first switch and opened by the closing of the latter.
7. The combination with an oil burner, an electric motor to drive the same and a thermostat operated switch to start and stop the motor, of spark electrodes for igniting the oil from the burner, a transformer to produce sparks across the electrodes and connected in circuit with said motor so as to be subject to control by said switch, a self closing switch also in circuit with the transformer and adapted when opened to cut out the transformer without stopping the motor, a second pair of spaced electrodes arranged adjacent the burner, electrical means adapted when energized to open the self closing switch, and a circuit from the transformer including said electrical means and said second pair of electrodes, a second electrical means adapted when energized to hold the self closing switch open, a circuit from the motor circuit connected in shunt therewith and adapted to supply said second electrical means, and a switch in said shunt supply circuit adapted to be closed by the opening of the self closing switch.
8. The combination with an oil burner, an electric motor to drive the same and a thermostat operated switch to start and stop the motor, of spark electrodes for igniting the oil from the burner, a transformer to produce sparks across the electrodes and connected in circuit with said motor so as to be subject to control by said switch, a self closing switch also in circuit with the transformer and adapted when opened to cut out the transformer without stopping the motor, a second pair of spaced electrodes arranged adjacent the burner, electrical means adapted when energized to open the self closing switch, and a circuit from the transformer including said electrical means and said second pair of electrodes.
9. In combination, a burner, means for starting and stopping the same, an ignition device having an active condition for ignition of the fuel from the burner and an inactive condition, means for rendering said device active simultaneously with the starting of the burner, electrical means effective when energized to render said device inactive and a series electrical circuit including said electrical means with an air gap and a source of high potential, whereby the air gap forms a break in said circuit, said air gap being subjected to the heat from the burner and when heated thereby permitting a flow of current across said gap to said electrical means.
